3,097,387 SCOURING PAD

Mark J. Perkovich, Chicago, Ill., assignor to General Foods Corporation, White Plains, N.Y., a corporation of Delaware

Filed May 18, 1960, Ser. No. 29,986

1 Claim. (Cl. 15—209)

This invention relates to a novel scouring pad. More particularly, the invention is concerned with a cleansing or scouring device employing metal wool filaments, such as steel wool, which device may have incorporated therein soap or a like saponaceous composition.

Metal wool, for example so-called steel wool, has gained wide acceptance for scouring household articles such as pots and pans. Scouring and polishing pads made of steel wool which have been matted or felted together or intertwined or interwoven into a mass of filaments, are marketed in a variety of sizes and shapes. The form of the pads must be such as to enable them to be easily gripped by a housewife to permit a proper scouring and polishing motion to be applied to the pads. In such use the pads are highly effective.

However, it will be seen that metal wool scouring pads used while being grasped present several undesirable characteristics. Metal wool, itself, is harsh and unpleasant to the touch. Rusting may occur after several immersions of a pad in water, and contact between the user's hand and rusted, wet, metal surfaces of the pad is disagreeable. Moreover, there is a tendency for metal wool to break or "splinter," which can result in slivers of the metal entering the skin of the user.

It has, therefore, long been a problem to provide a scouring pad with means enabling the pad to be gripped and manipulated in the scouring and polishing of pots and pans, such gripping means to be formed from material which will have no deleterious effect on the hand of a user and not be unpleasant to the touch. Furthermore, the gripping means must be such that it provides an easily grasped member, such as a handle, and must be economical to manufacture, since the gripping means will be discarded with its expended pad. Also, the gripping means must be firmly secured to a plurality of metal wool filaments so that through all normal uses of the pad the gripping means will remain in place on the pad.

It is a primary object of the present invention to provide a scouring pad which has a handle easily grasped by the user and firmly anchored on the pad.

It is another object of this invention to provide a scouring pad which has firmly affixed thereto gripping means formed from material which is pleasant to the touch and has no deleterious effect on the hand of a user.

It is still another object of this invention to provide a scouring pad which has firmly secured thereto a handle that permits the pad to be grasped by one hand of a user so that no portion of that hand contacts any abrasive surface of the pad.

It is a further object of this invention to provide a scouring pad having a handle which is relatively simple and inexpensive to manufacture and which is secured to the pad by means of a simple and distinctive manufacturing process.

An article or pad according to the present invention comprises a body of matted, interwoven, elongated, metal wool filaments, a backing with a handle thereon, and a flexible film fused to the backing and to filaments of the metal wool body of the pad.

The backing includes a relatively thin, flexible portion which overlies a surface portion of the body, and a handle joined to and extending away from the flexible backing portion and adapted to be manually grasped. In one distinctive embodiment the backing is formed from a

2

sheet member of relatively thin flexible material, and the handle portion of the backing is formed from a plurality of plies of the flexible material which have been joined together. The plurality of plies which form the handle portion may be formed when a central portion of the sheet is folded so that sheet portions adjoining the fold line are brought into face-to-face relationship. If the entire sheet member is precoated with a plastic film activatable to a flowable condition at an increased temperature, the adjoining portions will be firmly fixed together upon activation of the plastic film. In a preferred embodiment of the invention, end portions of the backing extend away from the handle on either side thereof and are integral with the adjoining sheet portions that form the plies of the centrally disposed handle. These end portions of the backing overlie a preferably substantially planar surface portion of the body of metal wool filaments and are secured thereto by means of the same precoated, activatable plastic film which serves to secure the plies of the handle to each other.

According to a distinctive feature of the invention, the backing is composed of flexible paper, which has a desirable amount of firmness so that it will resist disintegration upon strenuous use. A scouring pad in which this feature is embodied will likewise have a handle composed of two plies of paper with a film or films of plastic composition disposed between the plies. Along those lines where the plies of the handle portion are integrally joined to the end portions of the sheet of paper the sheet will be foldable, since it is composed of paper. In such a pad the handle portion may be folded to lie against one of the end portions of the sheet, thereby reducing the space occupied by the pad. Such folding permits the juxtaposition of the handle on the backing in substantially contiguous relation thereto during activation of the plastic film interposed between the backing and the body of filaments. This positioning greatly simplifies the apparatus which applies heat and pressure to the backing and film to activate the film and cause it to intimately contact the body of filaments. In addition, economies are effected in the size of containers for packaging the finished pads, since each pad occupies less space when it is packaged with its handle folded against one of the end portions of the backing.

When it is desired that the pad be utilized in a scouring operation, the handle portion may be folded away from its adjacent end portion and may be brought to a position substantially normal to the end portions of the sheet so that the handle is easily grasped by the fingers of a user.

It has also been found to be advantageous to provide a non-adhesive lacquer or plastic coating on that surface of the sheet member which will be contacted by a hand of the user in order to further mitigate any possibility of that hand contacting a surface which is unpleasant to the touch. Furthermore, if the entire upper surface of the backing from which the handle and end portions are formed is coated with a non-adhesive film, that film may be utilized to protect the paper backing from disintegration or curling due to contact with water, detergents, hot fluids, and other substances with which the paper might come in contact during conventional household uses of the scouring pad.

A plastic film which may be activated at increased temperatures and thereby flow is, as previously set forth herein, precoated on that surface of the backing which is to be brought into contact with the body of metal wool filaments. This film preferably has a thickness substantially equal to or greater than the largest cross-sectional dimension of the metal filaments and when activated is capable of receiving filament loops therein to the extent

that successive loops of a plurality of filaments will have the composition of the film fused therearound.

Thus, the film of plastic is so characterized that when the plastic is activated it will melt and flow around the filaments. As a result, the film and filaments are integrally interlocked to the extent that such interlocked filaments will be unwoven from the metal wool body should the backing film be pulled away therefrom and will in large measure remain anchored to the backing. The character of the anchoring can be described as one wherein a substantial plurality of the filaments at the surface of the body of matted metal wool penetrate the plastic film, emerge therefrom and reenter the film, thus locking successive loops of filaments so that the body of interwoven matted metal wool retains its aggregated form or shape.

To effect this structure the plastic of which the film is composed should be of high tensile strength as well as dimensional stability at least at temperatures below 140° F.; that is, at those temperatures normally encountered in household use. At such temperatures the plastic film should also remain relatively inert to the action of alkalis, hot water and soaps, and should be non-toxic, odorless and of such flexibility that, at the thickness required for proper interlocking of filament loops, the film alone or in combination with a backing sheet of paper, foil, woven fabrics or the like will be flexible in use.

The mass of metal wool is preferably composed of elongated filaments of steel, which filaments are intertwined or interwoven more or less randomly with respect to one another. The metal wool preferably also has incorporated therein some form of soap or saponaceous composition which serves as a lubricant as well as a detergent effecting appropriate scouring and polishing of pots and pans and similar articles. In accord with present commercial practices, the metal wool mass can be assembled into a suitable pad having an oval or rectangular outline and can be of a compressible, springy nature such that it will yield upon the application of pressure when the plastic film is being activated and interlocked with the metal wool filaments. The surface of the pad is preferably plane on that side of the pad which is to receive the plastic film, but may be rounded or sloping, particularly near the marginal edges of the pad.

The film may be composed of any suitable, activatable plastic which lends itself to liquefaction through the action of heat or a solvent, the plastic melting so that it receives filament loops within the plastic film and then solidifies to ensure interlocking. Although well-known adhesive resins can be activated by use of such solvents as hot acetone and methyl ethyl ketone, such adhesive resins and the solvents therefor are less preferred since their use introduces problems of solvent recovery and safety control. It is preferred to employ heat-activated adhesives so that heat can be applied to the free film, preferably through the backing; upon melting, the composition forming the free film will rapidly transfer its heat to the metal filaments, effecting a drop in temperature of the plastic after it is momentarily liquefied and migrated around successive loops of a plurality of interwoven metal filaments. Such compositions as the polymerized olefins, e.g., polyethylene, are preferably employed. Other suitable film compositions include microcrystalline waxes with added polyethylene; polyisobutylene with added paraffin; vinyl acetate; polyamides; butyl rubber emulsions, and like moisture-proof adhesive resins.

The film is preferably integrated with sheet material having properties usually found in fibrous cellulosic material or paper, i.e., flexibility and tendency to absorb quantities of plastic resins applied thereto. Although paper in the common or usual sense means a material made from such sources as wood, rag, or Bagasse (sugar cane), a broader interpretation of the term paper is intended herein, the term being understood to include such kindred materials as artificial and natural textile fibers

which are matted and woven. Also included in the term, paper, are composite structures made by laminating such paper or paper-like compositions to other sheets such as plastic films, metal foil and the like, which may be relied upon to offer an attractive appearance either through an applied design or the appearance of the material itself. As a rule, the paper backing sheet for use in combination with the backing film will be one capable of being printed and will range in weight from 8-90 lbs., preferably about 45 lbs. (basis 24 x 36, 500=3,000 sq. ft.).

Various kinds of paper that can be used are: papers made from chemical pulps including sulphate papers, sulphite paper, sulphate-sulphite combination papers, soda pulp papers, these various papers being either uncoated or coated on one or both sides with a coating comprising clay, titanium dioxide, and binder; papers made from chemical pulp or chemical pulp and groundwood combinations, coated or uncoated, which have been calendered or supercalendered, such as publishing papers, glassine, supercalendered sulphite papers, machine finish sulphite-sulphate papers, and machine finish and machine glazed sulphite-sulphate papers, and other materials such as cellulosic films including cellophane and cellulose acetate, foil and the like.

These and other objects, features and advantages of the present invention will become more apparent when taken in connection with the following detailed description and the illustration of a preferred embodiment of the invention in the accompanying drawings, which form a part hereof, and in which:

FIG. 1 is a side elevational view of a scouring pad according to the invention with a backing secured thereto;

FIG. 2 is a top plan view of the scouring pad of FIG. 1;

FIG. 3 is a vertical sectional view of the pad, taken along the line 3-3 of FIG. 2, and

FIG. 4 is an enlarged vertical sectional view of a backing and film according to the invention.

Referring now to the drawings, and in particular to FIGS. 1 to 3 thereof, the film 10, which is composed of a plastic composition that flows at increased temperatures, is illustrated in a position between and contiguous with a backing 12 and a body 13 of metal wool filaments. Plastic film 10 is secured to the backing 12 and to successive loops of a plurality of filaments of the body 13, thereby interlocking the backing 12 and the body 13 and maintaining those parts of the scouring pad in the relative positions shown in FIGS. 1 to 3.

To ensure a firm anchoring of the backing 12 to the body 13 through the intermediation of plastic film 10, a substantially planar portion 15 is formed on one surface of the body 13. During manufacture of a finished pad according to this invention, planar portion 15 provides a surface against which the backing 12 is pressed, and contact between the film 10 on the backing 12 and planar surface portion 15 is achieved over the entire area of the film available for such contact.

Plastic film 10 serves a function in addition to interlocking the backing 12 and body 13. As best seen in FIG. 4, central film portions 20 and 22 lie intermediate central backing portions 16 and 18 when the backing 13 has been folded to provide a handle 14 and end portions 30 and 32, which are integral with central backing portions 16 and 18 and extend at approximately right angles away from such portions. Where end portions 34 and 36 of the film 10 underlie backing end portions 30 and 32, the film serves to bond the backing 12 to the body 13; where central film portions 20 and 22 are interposed between central backing portions 16 and 18, the film serves to bond central backing portions 16 and 18 to each other to form handle 14.

According to the present invention, the entire sheet from which the backing 12 and handle 14 are formed may be precoated with an even layer of film 10 over one complete surface thereof. The sheet is then folded, as best illustrated in FIGS. 3 and 4, to bring adjoining central

portions 16 and 18 of the backing 12 into face-to-face relationship and to cause central film portions 20 and 22 to be brought into abutting position. As a result of such folding, end portions 30 and 32 of the backing 12 are disposed to form a substantially continuous plane surface provided with a substantially continuous layer of film on one side thereof, such layer being formed from film end portions 34 and 36. When so folded, the plastic film 10 may either have central film portions 20 and 22 activated at that time in order to permanently form handle 14, or central film portions 20 and 22 may be activated simultaneously with the activation of the end film portions 34 and 36 to secure the backing 12 to the body 13.

It will be observed that when the backing 12 is made from paper or other material which is flexible, folding the sheet of paper into a handle 14 and end portions 30 and 32 will be facilitated. To ensure maintenance of a substantially continuous film 10 after the sheet member has been folded in the form best seen in FIGS. 3 and 4, the film is preferably formed from an elastic material which will not crack or chip upon being manipulated. When a film of such composition is utilized, it will be possible to freely fold the handle 14 against either of backing end portions 30 or 32, even after the plastic film 10 has been activated. Such folding makes possible the temporary pressing of the handle 14 against an end portion of the backing 12 as the novel scouring pad of the present invention is inserted into a container. This foldability thus becomes an advantageous economic factor, since the entire space occupied by the pad of the invention is substantially reduced when the handle 14 is disposed contiguous to one of the backing end portions 30 and 32. When it is desired to use the scouring pad as a household article, the handle 14 is again brought to a position substantially normal to the backing end portions 30 and 32 to provide a member which is easily grasped by one hand of the user.

Advantageously, the body 13 is formed from a plurality of metal wool filaments which are interwoven or intertwined with one another and not merely matted or felted together. When the backing 12 is laminated to a body of matted filaments, the force exerted on the filaments during a scouring operation may be sufficient to cause an entire outer layer of these filaments to be pulled from underlying filament layers. In this event the backing 12 is either completely disassociated from the main body 13 of filaments or else dislocated with respect to the body so that effective scouring action cannot be obtained by grasping the backing alone.

The use of interwoven or intertwined filaments, on the other hand, results in a laminated structure in which the backing 12, film 10 and body 13 are united in a manner which enables the structure to resist disintegration under the application of forces such as those which arise in the course of a scouring operation. Interwoven or intertwined filaments have been found to have greater positional stability with respect to other filaments of the body. In addition, a force in a direction which might tend to loosen or unravel one or more filaments of a body of intertwined filaments will merely serve to enhance the stability of other adjacent filaments. Thus the unraveling action of

a multiplicity of forces on an interwoven or intertwined body will be unlikely to affect a sufficient number of filaments at any one time to cause disintegration of the body 13.

It will be understood that the terms "interwoven" or "intertwined" as used heretofore to describe the structure and arrangement of the metal filaments which form the body 13, are intended to have a broader meaning than that normally ascribed to a woven structure. Thus, the filaments of the body are not limited to a composite formation in which they extend in two directions only, as is conventional in other woven fabrics, but extend in more or less random relationship to each other. The filaments are intermingled so that they form a mass which is not easily unraveled. A body of filaments according to the present invention may be formed by rolling a metal wool strand upon itself to form a ball, the direction of convolution being varied at intervals during the balling of the material. After the steel wool has been rolled into a ball, it is then compacted to form the "interwoven" or "intertwined" filament body of the present invention.

While the present invention has been described with particular reference to a specific embodiment thereof, it will be understood that the invention is not to be limited by that embodiment, but its scope is to be defined only by reference to the following appended claim.

What is claimed is:

30 A scouring pad, comprising a body of matted interwoven elongated metal wool filaments having a substantially planar surface portion formed from said filaments, a backing including a continuous sheet of relatively thin flexible material adjoining central portions of which are folded into face-to-face relationship to form a handle, flat end portions of said sheet extending on either side of said handle and overlying said surface portion of said body, and a flexible film of high tensile strength and dimensional stability at temperatures below 140° F. precoated on one side of said sheet and activatable at increased temperatures, said film having been activated and thereby holding together said adjoining central portions of said handle, said film having a thickness greater than the diameter of said filaments at said surface portion and by said activation being fused to said end portions of said sheet and surrounding and being fused to a plurality of said filaments at said surface portion of said body to interlock said body and said backing.
